Assistant Examiner — Alison Davis

(57) **CLAIM**

The ornamental design for a computer case as shown and described.

DESCRIPTION

1. Computer case
- 1.1 : Perspective
- 1.2 : Perspective
- 1.3 : Front
- 1.4 : Back
- 1.5 : Left
- 1.6 : Right
- 1.7 : Top
- 1.8 : Bottom
- 1.9 : Enlarged
- 1.10 : Enlarged
- 1.11 : Enlarged
- 1.12 : Exploded

1. The dash-dash broken lines in the drawings depict the portions of the computer case that form no part of the

(Continued)

claimed design; 2. The dot-dash broken lines in the drawings depict the boundaries of the enlarged views and form no part of the claimed design.

1 Claim, 12 Drawing Sheets
